Primary Examiner — Elizabeth J Oswecki*(74) Attorney, Agent, or Firm* — C. G. Mersereau DeWitt LLP(57) **CLAIM**

The ornamental design for a face mask, as shown and described.

DESCRIPTION

FIG. 1 is a perspective view of a face mask showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof, shown with straps attached in broken lines in a used condition; and, FIG. 9 is another front elevation view thereof, shown on a human head in broken lines in a used condition.

The broken line shown in FIGS. 8 and 9 form no part of the claimed design.
